BIB

Alexander P. Elson, New York, N. Y.

Application February 8, 1937, Serial No. 124,577

1 Claim. (Cl. 2—49)

This invention relates generally to a device for use as a table bib for children although the said device hereinafter described can also be used by dentists, physicians and nurses to protect patients during work on the face and mouth.

The main object of the invention resides in the provision of a bib, apron or napkin which is preferably made of a crepe paper or other form of paper used ordinarily for napkins, towels and the like whereby the said bib may be discarded after each use thereof in similar fashion to paper towels or napkins.

Another object of the invention resides in the provision of a bib which can be made and packed cheaply. Another object of the invention resides in the provision of means for connecting the bib around the neck of the wearer in simple fashion.

These objects and other incidental ends and advantages of the invention will hereinafter appear in the progress of the disclosure and as pointed out in the appended claim.

Accompanying this specification is a drawing showing preferred forms of the invention wherein corresponding reference characters designate corresponding parts through the several views.

In accordance with the drawing:

Figure 1 is a front elevation of a paper blank for a bib suitably perforated for the formation of a neckband and scored for the folding of the said neckband and the lower edge to form a trap.

Figure 2 is a side elevation of Figure 1.

Figure 3 is a side elevation of Figure 1 showing the folding of the neckband and the lower edge along the lines of scoring.

Figure 4 is a top plan view of Figure 5.

Figure 5 is a front elevation of a bib in completed form.

Figure 6 is a side view of Figure 5.

Figure 7 is a front elevation of a modified bib in completed form.

Figure 8 is a side elevation of Figure 7.

Figure 9 is another modified bib in completed form.

Figure 10 is a side elevation of Figure 9.

In accordance with the drawing, and in accordance with the preferred forms of the invention shown therein, numeral 10 designates a blank of paper preferably, that type of crepe paper or other paper used ordinarily for napkins and towels, the said blank of paper being preferably in the form of a rectangle. Blank 10 below the upper edge thereof is provided with opposite V notches extending inwardly from the side edges, the upper legs of the V notch being designated by numeral 11 while the lower legs of the said

notch are designated by numeral 11'. Intermediate the upper edges 11 of the V notch and the upper edge of the blank 10 is a transverse scoring line 12 on the reverse side of the blank 10. When the upper portion of blank 10 is folded rearwardly along the scoring line 12, double ply encircling straps are formed having an outer ply 14 and an inner ply 13. The upper edge of the said double ply encircling straps is indicated by numeral 17 while the means of securing the 10 said straps around the neck of the wearer is indicated by numeral 18 which, as shown, consists of an adhesive material such as paste or the like.

Above the lower edge of the blank or body portion 10 is a transverse scoring line 15. The lower portion of the blank 10 below scoring line 15 is designated by numeral 16, being folded upwardly along the scoring line 15 to form a trap for any materials which are likely to flow or fall down the main body 10 of the bib.

Since crepe paper or other types of paper which are used to form paper napkins and towels lack resiliency, it has been found that by corrugating the intermediate portion of body 10 transversely, the bib resists flexing along longitudinal lines. 25 The corrugations on the body of bib 10 is indicated by numeral 19. It is, of course, understood that the paper comprising the bib must have a stiffness of body sufficient to take a corrugation which will prevent flexing along longitudinal 30 lines and which will permit flexing along transverse lines of the bib. The corrugations 19 serve another purpose in that they impede the flow or fall of feeding materials dropping from the mouth of the user. Where corrugations 19 are unsuccessful in this regard, trap 16 serves as a final catch-basin.

Figure 8 shows a bib which is similar in all respects to the bib shown in Figures 1, 2, 3, 4, 5 and 6 except that independent encircling straps 40 are provided which are affixed to a circular recess 20 in the bib body 10. Thus a tape member has portion 23 secured to recess 20 by such means as adhesive 26 while the protruding portions 21 and 22 of the said tape member project beyond the upper edge of the bib body 10 to be secured to each other at the terminals by any means such as adhesive paste 28.

In Figure 9, another type of bib is shown which substitutes a re-inforcing strip 26 for corrugations 19, the said re-inforcing strip 26 being secured to the front face of body 10 intermediate the width thereof by such securing means as adhesive material 27.

I wish it understood that minor changes and 55

variations in the material, integration and location of the several parts may all be resorted to without departing from the spirit of the invention and without departing from the scope of the appended claim.

I claim:

As an article of manufacture, a bib comprising a sheet of paper having transverse corrugations substantially intermediate the length thereof to

make the bib flexible along transverse lines and substantially inflexible along vertical lines, the said transverse corrugations also serving as obstructions for the easy flow of liquid and solid foods, the said sheet near the top being smooth and having recesses cut therein to form opposing encircling straps, the said sheet having its lower edge upturned to serve as a trap.

ALEXANDER P. ELSON.
